UNITED STATES PATENT OFFICE.

JOHN C. COOKE, OF PHILADELPHIA, PENNSYLVANIA, ASSIGNOR TO NEW YORK SHIPBUILDING COMPANY, OF CAMDEN, NEW JERSEY, A CORPORATION OF NEW JERSEY.

WATER-TUBE BOILER.

SPECIFICATION forming part of Letters Patent No. 714,867, dated December 2, 1902.

Application filed October 4, 1901. Serial No. 77,513. (No model.)

To all whom it may concern:

Be it known that I, JOHN C. COOKE, a citizen of the United States of America, residing in the city and county of Philadelphia, in the 5 State of Pennsylvania, have invented a certain new and useful Improvement in Water-Tube Boilers, of which the following is a true and exact description, reference being had to the accompanying drawings, which form a 10 part thereof.

My invention relates to water-tube boilers of the kind provided with duplex tubes secured in and projecting from a header, the 15 object of my invention being to provide a simple and efficient device for securing the tubes in place and one also which facilitates their ready removal.

The nature of my improvements will be best understood as described in connection 20 with the drawings in which they are illustrated, and in which—

Figure 1 is a sectional view through one of the duplex tubes, the head to which the said tubes are secured, and the parts of the header 25 in which the said tubes are secured. Fig. 2 is a cross-sectional view on the line 2 2 of Fig. 1. Fig. 3 is a longitudinal sectional view of the tube-head. Fig. 4 is a cross-sectional view on the line 4 4 of Fig. 3, and Fig. 5 is a 30 view of the device used for extracting the tubes and tube-head from the header.

A and A' are respectively the inner and outer walls of the header, A² indicating the intermediate partition usual where duplex 35 tubes are employed. The inner wall A of the header is formed with an outwardly-converging conical opening or hole a, and opposite to this hole, in the outer wall A' of the header, is formed a hand-hole a' for the insertion of 40 the tubes, the said hole being preferably of the same elliptical form indicated in Fig. 2 and having preferably its inner face A⁴ projecting slightly from the face of the wall, as shown.

45 A⁵ A⁵ indicate lugs formed on the outer face of the wall A', as indicated.

B is the tube-head, preferably formed of a malleable casting and having an annulus B', to which the outer water-tube is secured, the

said annulus preferably fitting in a perforation a² of the intermediate partition A², as shown. The two rings B' and B⁴ are connected by braces or arms B³ B³, while from the outer end of the ring B⁴ extend arms B⁵ B⁵, supporting a transversely-extending head or 55 brace B⁶, which is preferably formed in an internally-threaded perforation, as indicated at b⁶. The inner water-tube is preferably secured to the ring or annulus B⁴ by screwing into its internally-threaded opening b⁴, and 60 the outer water-tube is preferably secured to the ring or annulus B' by screwing onto the externally-threaded portion (indicated at b') and abutting against the shoulder, (indicated at b²), the head or end of the external pipe 65 thus forming practically a continuation of the ring B' and being formed to fit the conical opening a in the wall of the header. The external tube may be secured to the head in any convenient way, though it is always necessary that the head should either directly or 70 indirectly form a tight fit in the conical opening a.

C, as shown in the drawings, is both a lid and brace fitting on the inside of the perforation a and formed with an internally-threaded perforation C², C' indicating the fitted face, which rests upon the rim A⁴. 75

E is a bolt screwing into the threaded perforation C² and having an extension E', which 80 rests upon the head B⁶, E² indicating the head of the bolt, which obviously when screwed into the lid-brace C will thrust the head B outward, clamping it tightly in the perforation a and at the same time will thrust the 85 lid-brace C hard against its seat on the outer wall. By preference I make the bolt E with an outward extension E³, threaded at its outer end, as indicated at e³, and extending through an unthreaded perforation d of a 90 dog D, the arms D' of which rest against the outside of the wall A' in the spaces between the lugs a⁵.

95 F indicates a nut screwing upon the threaded extension E³ and against the dog D, and it will be obvious that this nut has the effect of drawing the lid-brace C tight against its bearing.

I indicates the inner tube, having its inner end *i* threaded and screwing into the ring B⁴ and its outer end provided with arms or projections I', which center it in the outer tube, 5 which outer tube is indicated at J and is formed with a head J', screwing onto the ring B' and fitting in the conical perforation *a*. The outer end J² is closed by a cap K, screwing onto its threaded portion *j*².

- 10 H is a bolt having its end threaded, as indicated at *h*, and a head H'. When it is desired to withdraw the tubes, the bolt E and lid-brace C are removed and the bolt H inserted through the perforation *b* of the dog D 15 and screwed into the perforation *b*⁶ of the head B⁶, the head H' resting against the brace D. Obviously the action of the bolt H will thus be to draw the head B outward until the tight fit in the header-wall A is loosened, 20 when both head and attached tubes can be readily removed through the hole *a*'.

Having now described my invention, what I claim as new, and desire to secure by Letters Patent, is—

- 25 1. In a water-tube boiler, a header having an outwardly-converging conical hole *a* in its inner wall and an oppositely-disposed hand-hole, as *a*', in its outer wall in combination with a duplex tube-head said head having an 30 annular rim B' adapted to make a close fit in the hole *a* when thrust outward and to support an outer water-tube, an inner annulus B⁴ adapted to support an inner water-tube and a head B⁶ situated entirely within the 35 header, a brace spanning the hole *a*' on the inside of the header, means acting against said brace and the head B⁶ to thrust the tube-head against the inner wall of the header and outer and inner water-tubes secured to the 40 rims B' and B⁴.

2. In a water-tube boiler, a header having an outwardly-converging conical hole *a* in its inner wall and an oppositely-disposed hand-hole, as *a*', in its outer wall in combination 45 with a duplex tube-head, said head having an annular rim B' adapted to make a close fit in the hole *a* when thrust outward and to support an outer water-tube, an inner annulus B⁴ adapted to support an inner water-tube 50 and a head B⁶, a lid and brace C spanning the hole *a*' on the inside of the header, means acting against said lid and brace and the head B⁶ to thrust the tube-head against the inner wall of the header and outer and inner water- 55 tubes secured to the rims B' and B⁴.

3. In a water-tube boiler, a header having an outwardly-converging conical hole *a* in its inner wall and an oppositely-disposed hand-hole, as *a*', in its outer wall, in combination 60 with a duplex tube-head said head having an annular rim B' adapted to enter the hole *a*, an inner annulus B⁴ and a head B⁶, an outer water-tube J secured to the outside of the rim B and adapted to fit in the conical hole 65 *a*, an inner tube secured to the annulus B⁴, a brace spanning the hole *a*' on the inside and means acting against said brace and the head

B⁶ to thrust the tube-head toward the inner wall of the header and clamp the outer tube in hole *a*. 70

4. In a water-tube boiler, a header having an outwardly-converging conical hole *a* in its inner wall, and an oppositely-disposed hand-hole, as *a*', in its outer wall in combination with a duplex tube-head said head having an 75 annular rim B' adapted to make a close fit in the hole *a* when thrust outward and to support an outer water-tube, an inner annulus B⁴ adapted to support an inner water-tube and a head B⁶, formed with a threaded perforation *b*⁶, a brace spanning the hole *a*' on the inside of the header, means acting against said brace and the head B⁶ to thrust the tube-head against the inner wall of the header and outer and inner water-tubes secured to the 85 rims B' and B⁴.

5. In a water-tube boiler, a header having an outwardly-converging conical hole *a* in its inner wall and an oppositely-disposed hand-hole as *a*' in its outer wall in combination 90 with a duplex tube-head said head having an annular rim B' adapted to make a close fit in the hole *a* when thrust outward and to support an outer water-tube, an inner annulus B⁴ adapted to support an inner water-tube 95 and a head B⁶, a lid and brace C arranged to span the hole *a*' on the inside of the header and formed with a threaded perforation C² and a bolt screwing in said perforation C² and abutting against head B⁶. 100

6. In a water-tube boiler, a header having an outwardly-converging conical hole *a* in its inner wall and an oppositely-disposed hand-hole as *a*' in its outer wall in combination with a duplex tube-head said head having an 105 annular rim B' adapted to make a close fit in the hole *a* when thrust outward and to support an outer water-tube, an inner annulus B⁴ adapted to support an inner water-tube and a head B⁶, a lid and brace C arranged to 110 span the hole *a*' on the inside of the header and formed with a threaded perforation C², an outer dog D formed with an unthreaded perforation *d*, a bolt E screwing into the perforation C² and abutting against the head B⁶ 115 said head having an extension E³ extending through the dog D and threaded at its outer end, and a nut screwing on said extension E³. 120

7. In a water-tube boiler, a header having an outwardly-converging conical hole *a* in its inner wall and an oppositely-disposed hand-hole as *a*' in its outer wall in combination with a duplex tube-head said head having an 125 annular rim B' adapted to make a close fit in the hole *a* when thrust outward and to support an outer water-tube, an inner annulus B⁴ adapted to support an inner water-tube and a head B⁶, formed with a threaded perforation *b*⁶, a lid and brace C arranged to 130 span the hole *a*' on the inside of the header and formed with a threaded perforation C², an outer dog D formed with an unthreaded perforation *d*, a bolt E screwing into the perforation C² and abutting against the head B⁶ 135

said head having an extension E³ extending through the dog D and threaded at its outer end, and a nut screwing on said extension E³.

8. The duplex tube-head B having an externally-threaded annulus B', the internally-threaded annulus B⁴ and the transversely-extending head B⁶.

9. The duplex tube-head B having an ex-

ternally-threaded annulus B', the internally-threaded annulus B⁴ and the transversely-extending head B⁶ formed with a threaded perforation b⁶.
